ATTORNEY.

UNITED STATES PATENT OFFICE.

JOHN J. DAVIS, OF ST. LOUIS, MISSOURI.

MOP-WRINGER.

No. 921,207.

Specification of Letters Patent.

Patented May 11, 1909.

Application filed July 2, 1908. Serial No. 441,602.

To all whom it may concern:

Be it known that I, JOHN J. DAVIS, citizen of the United States, residing at St. Louis, State of Missouri, have invented certain new and useful Improvements in Mop-Wringers, of which the following is a full, clear, and exact description, reference being had to the accompanying drawings, forming a part hereof.

10 My invention has relation to improvements in mop-wringers; and it consists in the novel construction and arrangement of parts more fully set forth in the specification and pointed out in the claim.

15 In the drawings, Figure 1 is a side elevation of the wringer secured in position on a tub; Fig. 2 is a vertical cross section on the line 2—2 of Fig. 1; Fig. 3 is a vertical cross section on the line 3—3 of Fig. 1; Fig. 4 is a 20 rear end view, with part of arresting arm or stop broken away; and Fig. 5 is a perspective of the bracket carrying the locking-latch for the wringer-frame.

The object of my invention is to construct 25 a mop-wringer which can be conveniently swung out of the way for gaining access to the operating parts for purposes of cleaning, or be as readily locked to the tub when occasion arises to operate the wringer; all as will be 30 more fully apparent from a detailed description of the invention which is as follows:

Referring to the drawings, T, represents a tub or other vessel in which is contained the water. Secured along the wall of the tub is 35 a bracket 1, and diametrically opposite thereto is a bracket 2, between suitable ears e of which are mounted a lower pair of cylinders 3, 3, the bracket 1 having a centrally disposed lug 4 to which is hinged one arm of a 40 U-shaped wringer-frame F. The arm at the free end of this frame is extended sufficiently to permit the slot or socket a formed therein to engage and lock with the wedge-shaped keeper 5 formed on the inner face of the 45 bracket 2 between the ears e e. This arm of the frame F is springy so it can automatically ride over the inclined face of the keeper as the frame is swung downward, the arm

springing into its locked position when the keeper 5 comes fully opposite the slot a.

50 Mounted in elongated slots d d of the frame arms is the shaft S of the corrugated wringer roller 6, one end of the shaft being provided with an operating handle H. The roller 6 is spanned by a yoke 7 to which are secured the 55 plungers 8, 8, around which are coiled the expansion springs 9, 9, their ends bearing respectively against the yoke 7 and the frame F. As the crank H is turned, rotation is imparted to the roller 6, which in turn rotates 60 the cylinders 3, 3, the mop passing between the latter and the roller 6 compressing the springs 9, 9 according to the thickness of the material operated on. To disengage the roller 6 from the cylinders 3, 3, the free arm 65 of the frame F is released from the keeper 5, and the entire frame is swung upward (see dotted position Fig. 1), being arrested when 70 swung to the proper angle by the stop or arm 1 secured to the tub opposite the bracket 1.

The device will make an admirable clothes-wringer.

Having described my invention what I claim is:—

In combination with a vessel or tub, a U-shaped frame having one end hinged above the upper edge of the tub, a bracket for said hinged end, a second bracket fixed to the tub diametrically opposite the first bracket, a keeper on said second bracket for locking the 75 free end of the frame thereto, a pair of cylinders, mounted between the brackets, a wringer-roller having a shaft passing through suitable slots in the frame, a yoke spanning the roller, plungers carried by the yoke and 80 passing loosely through the hinged frame, springs encircling the plungers, and interposed between the yoke and hinged frame, the parts operating substantially as set forth.

In testimony whereof I affix my signature, 85 in presence of two witnesses.

JOHN J. DAVIS.
